UNITED STATES PATENT OFFICE.

HADWEN SWAIN, OF SAN FRANCISCO, CALIFORNIA.

GAS OR OIL ENGINE.

SPECIFICATION forming part of Letters Patent No. 650,571, dated May 29, 1900.

Application filed August 5, 1898. Serial No. 687,877. (No model.)

To all whom it may concern:

Be it known that I, HADWEN SWAIN, a citizen of the United States, residing at San Francisco, in the county of San Francisco and State of California, have invented certain new and useful Improvements in Gas or Oil Engines; and I do hereby declare the following to be a full, clear, and exact description of said invention, such as will enable others skilled in the art to which it most nearly appertains to make, use, and practice the same.

In the accompanying drawings, which form part of this specification, Figure 1 represents a side elevation of the engine; Fig. 2, an end view of part of sparking device; Fig. 3, perspective of sparking-point; Fig. 4, enlarged detail of sparking device; Fig. 5, sectional detail of governing device.

In Fig. 1, *g* represents the two-to-one cam that operates the exhaust-valve in most gas-engines. As I make no claim on this mechanism, connections and valve are not shown. A crank-pin located on this cam operates the connecting-rod *n*, which is pivoted to *e*. The latter slides freely back and forth inside the pipe *k*, one end of which is supported by the bracket *m* and the other pivoted to the lever *h* at the point *j*. The lever *h* is a bent lever, with a pivot at *i* and the outer end impinging on the inlet-valve *t*. When *k* is given a back-and-forth motion, it causes *t* to open, a spring closing it. There is no direct connection between *k* and *e*, operated by the rod *n*, the connection being made by interposing *l*, which is connected to the governor and which is by preference wedge-shaped, in a slot through *k* and *e*. The slot in *e* is longer than the width of *l*, so it only impinges on the latter when it nears one end of the stroke. *l* in turn being forced against one side of the slot in *k* gives the latter a forward-and-back motion, different positions of *l*, should this latter be wedge-shaped, giving more or less opening to the inlet-valve *t*, according to the speed of the engine, thus regulating it.

To the free end of *e* is fastened the arm *d*, to the top of which is pivoted the sparking-hammer *p* at *d'*. During most of the stroke *p* is held firmly against the stop *f* by the spring *c* sliding back and forth on it when operated by *n*. During the remainder of the stroke the latch *b*, having an incline at one

end impinging against the incline *v* on *p*, causes the latter to rise up until it is pulled off the edge of *b*, when the tension of the spring *c* causes it to fall and deliver a blow on *s*.

The shaft *s'* passes through part of the engine into the exploding-port, preferably into the inlet-port, and carries on its inner end the sparking-point *r*, the spark being made by the contact of the point on *r* and the adjusting-screw *q*. Fastened to the outer end of *s'* is *s*, which has an extension at its lower end for the purpose of attaching the spring *u*, the outer end of which is attached to *b* and serves to keep the latter in an upright position against the stop *a*, but allows *b* to describe part of a circle to escape *v* during the backward stroke of *p*. The spring *u* is lighter than *c*, and when *p* raises it causes *s* to follow until *r* touches *q*, when *p* leaves *s* and still lifts a slight amount before dropping off of *b* and driving *s* back to its original position by the extra weight of the spring *c*, thus producing the spark, the shaft *s'* having a slight oscillating movement. In order to time the spark, an adjusting-screw *z* is provided to move *p* forward or back, *w* serving to hold *z* from jarring out of position.

Having thus described my invention, what I desire to cover by Letters Patent is as follows:

1. In a gas or oil engine a connecting-rod *n* operated by a crank and a sliding rod *e* operating the sparking-hammer *p* having an incline *v* in combination with latch *b* operating sparking-point *r* through rock-shaft *s'* and *s* substantially as described.

2. In a gas or oil engine a connecting-rod *n* and a sliding rod *e* together with the latch *b* having stop *a* and flexibly connected to part *s* in combination with sparking-hammer *p* operated by a spring *c* substantially as described.

3. In a gas or oil engine a connecting-rod *n* operated by a crank and a sliding rod *e*, operating the sparking-hammer *p*, having an incline *v* operated by a latch *b* in combination with an adjusting-screw *z* with tightener *w* substantially as described.

HADWEN SWAIN.
